UNITED STATES PATENT OFFICE.

LEONARD KEBLER, OF BRONXVILLE, NEW YORK, ASSIGNOR TO WARD LEONARD ELECTRIC COMPANY, A CORPORATION OF NEW YORK.

RHEOSTAT.

Application filed April 8, 1920. Serial No. 372,150.

To all whom it may concern:

Be it known that I, LEONARD KEBLER, a citizen of the United States, residing at Bronxville, in the county of Westchester 5 and State of New York, have invented certain new and useful Improvements in Rheostats, of which the following is a specification.

This invention relates to rheostats having a series of contacts with adjustable means for controlling the resistance in the circuit as desired. It more particularly relates to regulating rheostats adapted to be mounted upon a panel or other suitable support. 15

One object of the invention is to provide a construction of units adapted to be built up and added one to the other to provide a total number of units for securing the 20 degree and character of control desired; and to accomplish this by a simple construction which may be utilized and assembled by the manufacturer or the user. A further object is to provide a construction 25 which is adapted to be mounted upon the front or the back of the panel board without change in the construction of the rheostat so that the same device may be sold and purchased for either character of mounting. 30 Another object is to provide a construction which may be used either as an open or enclosed type, as desired, using the same rheostat units in either case.

Other features of my invention include 35 the provision of a terminal block for each rheostat unit with provision for the leads as required for one or more units and the connections between them; also to avoid the use of an auxiliary stop for the contact 40 arm by causing the terminal block to also serve as a stop. Another object is to insure the shaft of each unit being dead and insulated from all parts. Another object is to provide an improved character and 45 form of contact means and its mounting in the contact arm with a view to securing simplicity in construction and assembly and a high degree of contact.

Another object is to provide a simple 50 form of coupling between units and of a character that will permit adjustment so that the movable contacts will all be aligned, or make contact on their respective units which will properly correspond with the

contacts made at the same time on other 55 units. Another object is to provide a scale and pointer of simple construction for indicating to the user the adjustment secured or, if desired, showing the motor speed which corresponds to any particular adjustment; and to so construct the scale and pointer that it may be conveniently used or removed without the necessity of change in the structure of other parts.

Another important object is to provide a 60 construction for readily permitting proper alignment of the shaft so that it will be perpendicular to the plane of the faces of the fixed contacts so as to insure a uniform 65 contact of the contact shoe therewith in all 70 positions of adjustment. These and other 75 objects and advantages of my invention will be understood from the following description and accompanying drawings illustrating a preferred embodiment thereof.

Fig. 1 is a vertical section illustrating two 80 units assembled and enclosed and mounted on the back of the board. Fig. 2 is a rear elevation of one of the rheostat units detached. Fig. 3 is a front elevation of the center bearing of a unit detached. Fig. 4 is a rear elevation of the same. Fig. 5 is a front elevation of the central portion of the plate of a rheostat unit which receives the center bearing. Fig. 6 is a sectional 85 view of the coupling between the movable elements of two rheostat units. Fig. 7 is a front elevation of a scale plate detached. Fig. 8 is a side elevation thereof. Fig. 9 is a front elevation of the pointer detached. Fig. 10 is a side view thereof. Fig. 11 is a side view showing one unit enclosed and mounted on the front of the board, and Fig. 12 is a side elevation showing two units mounted on the front of the board and not 90 enclosed.

The rheostat unit is especially adapted for 95 readily being mounted upon the face or back of the board and for being assembled one behind the other to any extent desired. In 100 the particular construction here illustrated, it comprises a sheet iron plate 1 having a turned up outer edge or rim 1'. The inside of the sheet iron plate is covered with a coating of insulating material upon which 105 is located the resistance connected to a series of circularly arranged contacts 2. The resistance elements are covered with a coat-

ing of vitreous enamel but as this construction of the resistance element and arrangement of the fixed contacts forms no part of the present invention, it need not be particularly referred to and of course other suitable construction might be used. The resistance plate has a central circular opening, in which three sector shaped extensions 1" extend spaced apart equally as shown 10 in Fig. 5. These extensions are integral with the iron plate and bendable relatively to each other in or out for the purpose hereinafter explained.

A center bearing 3 preferably of molded 15 insulating material carries the shaft 4 of the movable contact arm. This center bearing fits within the plate 1 and is secured to the extensions 1". It has three sector shaped inner extensions 3' which loosely fit 20 and extend through the sector shaped openings of plate 1 between the extensions 1". The recesses in the bearing block 3 receive the extensions 1", which engage the bottom of these recesses, the bearing block being 25 secured to these extensions by screws and nuts 5, the screws passing through holes 5' in the bearing block and having their heads counter-sunk in the face of the block and engaging nuts 5" on the inside of the extensions 1".

This support of the bearing block on the central extensions of the plate, which extensions are somewhat flexible and bendable, permits the bearing block to be adjusted by 35 tilting it and correspondingly bending the extensions 1" until the axis of the shaft 4 is perpendicular to the plane of the face of the resistance contacts 2, the extensions 1" being sufficiently stiff to retain their final 40 position of adjustment in later use of the device. This insures a uniform contact of the contact shoe with the resistance contacts in all angular positions of the contact arm. It will be noted that the rim of the 45 bearing block is undercut somewhat to permit sufficient adjustment or tilting of the block to give the required alignment of the shaft.

In the rear face of each extension 3' of 50 the bearing block is formed a hole 6. A contact ring 7 is carried on the inner face of the bearing block and has three extensions 7' which are received respectively by the three holes 6, which thus serve to position 55 contact ring 7 and which is held against the bearing block by the pressure of the contact shoe. The upper extension 3' of the block has formed therein the opening 6' which connects with the upper hole 6 and serves 60 as a pathway for the terminal lead 8 which is electrically connected with the ring contact 7 by means of the tongue or extension 7', which enters the upper hole 6.

The rim of the bearing block has cut 65 away portions as shown at 9 and on the in-

ner face of the bearing block rim are recessed portions 10 angularly spaced from the cut away portions 9. The scale plate which is adapted to be carried by the bearing block is shown in Figs. 7 and 8. It consists of a sheet metal ring 11 dished as indicated in Fig. 8. The plate has three inwardly extending tongues 11', which are spaced to correspond with the cut-away portions 9 of the bearing rim and are adapted to pass through these cut-away portions when the scale plate is placed over the bearing block. The scale plate is then turned angularly, the tongues 11' being pressed inwardly so as to permit them to pass under 80 the rim of the bearing block until they come respectively opposite the recesses 10. They then snap outwardly to seat in these recesses and securely lock the scale plate in place on the bearing block as shown in Fig. 11. 85 In cases where the rheostat is mounted on the back of the panel board as shown in Fig. 1, the plate 12 which is secured to the board by screws is similarly provided with an under-cut rim and cut-away portions 9 and recesses 10 so that the scale plate 11 may be similarly applied to the plate 12 when desired.

The handle 13 of the rheostat shown in Figs. 1 and 11 is preferably of molded insulation having an inner hole to receive the shaft of the rheostat and held in place thereon by a central screw 14. The shaft receives a cotter pin 15 which is located in a cross-wise recess 13' in the inner end of the handle and thus effectively locks the handle to the shaft. The pointer 16 for the scale plate is shown in Figs. 9 and 10 and has a central opening 16' through which the shaft of the rheostat passes and has lateral projections 16" which extend into the ends of the recess 13' of the handle. Thus when the handle is secured to the rheostat shaft it also locks in place the pointer 16 between the inner end of the handle and the plate 12 or bearing block 3 as the case may be as shown in Figs. 1 and 11.

The inner end of the rheostat shaft 4 has a flattened knurled head 4'. The contact arm 17 is of molded insulation molded about 115 the head 4' of the shaft and thus securely fixed thereto. The contact shoe 18 carried by the contact arm is of sheet metal with two strips 18' integral therewith bent at right angles to the plane of the shoe and extending into a hole 17' in the contact arm and in a recess 17" at the end of the contact arm. The contact shoe is thus carried by the arm in its movement, but is freely movable so as to make good electrical engagement with the fixed contacts. Formed in the contact arm is a rectangularly shaped recess 19 in which is seated a spring 20. This spring is preferably formed as shown in Fig. 1 having one leg engaging the contact 120 125 130

shoe over or near the contact ring 7 and thence extending to the outer part of the recess 19 where it seats and forms a coil 20' and then continues to the inner end of the recess and forms another coil 20'' from which the other end or leg of the spring extends outwardly to engage the contact shoe over or near the fixed contacts 2. This simple form of duplex coil spring with oppositely extending legs thus causes the contact shoe to be pressed against the fixed contacts and the contact ring so that in all positions a good electrical contact between the parts is obtained and the contact shoe is permitted to ride over and adapt itself to any unevenness in the contacts. This assemblage of the contact shoe and spring in the contact arm also permits the parts to be readily placed in position. The rheostat shaft has a circumferential groove engaged by a spring clip 21 at the face of the bearing block and thus retains the rheostat shaft in fixed position axially and gives the required pressure to the contact arm and spring upon the movable contact against the fixed contacts. The spring clip 21 is U-shaped and permits the shaft to be easily removed when desired by merely forcing the spring clip out of the groove in the shaft. The terminal block 22 is mounted at the top of each rheostat unit at the back of the plate and is preferably of porcelain or molded insulation of the form shown in Figs. 1 and 2. It is shown as having two side extensions 22' which are perforated to receive the terminal screws 23 and which pass radially through the extensions 22' to receive nuts 23', which are located in recessed slots on the outer face of the extensions. The terminal block is secured to the back of the rheostat unit by a central screw 24 which passes through the plate 1 and engages a nut 24' seated in a slot upon the back of the terminal block. On the front face of the terminal block is a circular groove 25 which is opposite a hole 26 through the rheostat plate, the groove 25 forming a passage for leads when desired, which enter through the hole 26 and pass through the groove 25 out through the bottom of the terminal block and then connected to the terminals on the block. In case the hole 26 and groove 25 is not used for this purpose, the hole 26 is conveniently covered by a plate 27 such as the name-plate of the manufacturer, which is held in place by the screw 24. The terminal block 22 also has a depending projection 28 which extends into the path of the contact arm 17 and thus serves as a stop for the contact arm in either direction of movement to prevent the operator from turning the arm beyond the initial or final resistance contact in either direction of movement. Referring to Figs. 1 and 2, it will be seen that the rim 1' of each rheostat unit is perforated in this example at three equi-distant points, through which pass screws 29 having nuts 29', the perforations being sufficiently near the rear face of the rheostat plate to prevent the nuts 29' from turning when the screws 29 are turned for convenience in assembling. When a single unit is used and mounted at the rear of a panel board as shown in Fig. 1, supports 30 are used, which are preferably of sheet metal bent in the form of a trough for stiffness and having outwardly extending portions 30' bent at right angles and slotted to receive screws 31, which pass through the panel board and having nuts 31', which engage the extensions 30'. The outer end of the supports 30 have slotted extensions 30'' adapted to receive the screws 29. The outer end of each shaft 4 of the rheostat unit is tapped to receive a central screw for retaining the handle coupling and likewise drilled on a diameter to receive a cotter pin. Where the unit is mounted on the back of the board, a coupling sleeve 32 is connected to the rheostat shaft 4 by a cotter pin 33 and to an extension shaft 34 by a set screw 35 in the form shown in Fig. 1. In case the unit is mounted on the front of the board, the sleeve 32 and extension shaft 34 is not used and the handle 13 is mounted directly on the rheostat unit shaft 4 as shown in Fig. 11, the handle 13 being attached directly to the shaft 4 by the central screw 14 and a cotter pin 15 being passed through the shaft 4 for locking the handle thereto. In Fig. 1, two rheostat units are assembled and are shown enclosed. The cylinder 36 of sheet metal in this case serves as the spacer and support for the second rheostat unit shown at the left of Fig. 1 and also to enclose the parts between the two units. This cylinder 36 is provided with open slots at its edges to receive the screws 29 of the two units which clamps the parts together. The second unit of Fig. 1 is enclosed by a sheet metal cylindrical box 37, the edges of which are slotted to receive and be clamped in position by the screws 29. The upper part of the box 37 above the terminal block 22 is cut-away and covered by the sheet metal auxiliary box 38 which has an extension 38' at each end, by which it is secured to the box 37. This auxiliary box 38 has a central opening 38'' at the top for receiving the incoming leads to the regulator which are conveniently connected to the terminals of the terminal block already described. The electric connections between the two rheostat units may be made from one terminal block to the other by leads from the terminals of the rear terminal block passing out through the groove 25 of the rear terminal block and through the hole 26 of the rear rheostat unit directly to the terminals of the terminal block 22 of the

inner rheostat unit. The units are operatively coupled together mechanically by the coupling shown in Figs. 1 and 6. This consists of a sheet metal element 39 bent in the 5 form of a trough and connected to the shaft 4 of the rheostat by a cotter pin 40 which passes through the rheostat shaft and the sides of element 39. The element is further secured to the shaft by a screw and washer 10 41, 41'. The outer end of coupling element 39 has two extensions or legs 39' which engage opposite sides of the outer end of contact lever 17 of the adjoining rheostat unit as indicated in Fig. 1. These legs or extensions 15 39' are bendable sidewise which affords means for sufficient relative adjustment of one contact arm of a unit to the contact arm of the unit to which it is coupled for securing proper alignment or relationship 20 to give proper or desired relative contact of the contact shoes on the respective units.

In Fig. 1 only two units are shown assembled, but it is evident that the construction 25 and relationship of the parts is such that any desired number of units can be similarly grouped together. Thus if an additional unit were to be added to the two shown in Fig. 1, another cylinder 36 would be added 30 over the left-hand unit and a third unit with an enclosing casing 37 added at the outer end of the second cylindrical element 36. In case the units are not to be enclosed, the enclosing box 37 at the rear of the last unit is 35 omitted and the cylinders 36 are replaced by spacing strips which would be engaged by the screws 29 in the same way as the enclosing casing.

In Fig. 11 one unit enclosed is shown 40 mounted on the front of the panel board. The same box 37, which is used for enclosing the outer unit when mounted on the rear of the board is used when mounted on the front. For front mounting the boxes 37 are 45 provided with offset feet 42 and supported on the board as shown in Fig. 11, the handle 13 being applied directly to the shaft 4 of the rheostat unit. Thus the same box 37 is constructed to serve as the enclosing box of 50 the last unit for rear board mounting and for enclosing and supporting the unit nearest the board for front board mounting. It is evident that if an additional unit were to be added to the one shown in Fig. 11, the 55 handle 13 would be removed and replaced by the coupling element 39, which would engage the contact arm of the unit added in front of the one shown in Fig. 11, and the handle would be applied directly to the shaft 60 4 of the front unit. The enclosing cylinder 36 would serve to enclose and support the front rheostat unit from the rear unit in a manner corresponding to that shown in Fig. 1. Similarly, additional units could be add- 65 ed if desired.

Fig. 12 illustrates two units coupled together when mounted on the front of the board and unenclosed. The supports 30 previously described are mounted on the front of the board and support the first unit. The 70 second unit is supported from the first unit by supporting strips 43, which are engaged by the screws 29 of the first unit and similar screws 29 of the second unit. The supporting strips 43 are preferably of the same 75 form as the supports 30, except that the extension 30' instead of being bent at right angles is left in the plane of the support. The units are operatively coupled as already described, the handle 13 being applied 80 to the shaft 4 of the front unit. Additional units could be similarly added and built up if desired.

It is evident from the above description 85 that I have provided a construction of rheostat unit, and co-operating means which are adapted to be built up to any extent desired for front or rear mounting and either open or enclosed. Also the various features of 90 improvement are such as to secure simplicity in manufacture and assembling of the parts and secure an efficient and durable construction.

Although I have described one embodiment 95 of my invention, various modifications may be made therein without departing from the scope thereof.

I claim:

1. A rheostat unit comprising a plate supporting the resistance elements, supporting elements for supporting said unit from a panel board, and means for connecting the outer ends of said supporting elements to the outside edge of said plate.

2. A rheostat unit comprising a plate supporting the resistance elements, said plate having an edge portion turned at right angles thereto, supporting elements for supporting said unit from a panel board, and means for connecting the outer ends of said supporting elements to said edge portion of said plate.

3. A rheostat unit comprising a plate supporting the resistance elements, said plate having a circumferential rim at right angles to the plate, supporting elements for supporting said unit from a panel board, and means passing through said rim for connecting the outer ends of said supporting elements to said rim.

4. A rheostat unit comprising a plate supporting the resistance elements, and means whereby said plate may be secured to the front or back of a panel board comprising fastening means engaging the outer edge of said plate.

5. A rheostat unit comprising a plate supporting the resistance elements, and means whereby said plate may be secured to the front or back of a panel board comprising

100

105

110

115

120

125

130

- fastening elements at the periphery of said plate extending in a direction parallel with the plane of said plate.
6. A regulator comprising a plurality of rheostat plate units parallel to each other, means engaging the peripheries of the plates of said units for supporting and spacing said plate units one from the other, and fastening elements passing through said means for securing same to said units, said fastening elements extending in a direction parallel with the planes of said plate unit.
7. A rheostat unit comprising a plate supporting the resistance elements and fastening means on the periphery of said plate, whereby said unit may be supported from another similar unit and also supported from a panel board.
8. A rheostat unit comprising a plate supporting the resistance elements, supports for supporting said unit on a panel board, an enclosing casing for said unit, and fastening means for connecting said supports with the edge of said plate and for also securing said casing to the edge of said plate.
9. A rheostat unit comprising a plate supporting the resistance elements, means for supporting said unit from the back of a panel board and embracing the periphery of said plate, and a casing enclosing said unit and also embracing the periphery of said plate.
10. A rheostat unit comprising a plate having fixed contacts thereon, a contact arm, a shaft supporting said arm, and means comprising bendable metal for aligning said shaft perpendicular to the plane of the face of said fixed contacts.
11. A plurality of rheostat units each comprising a supporting plate and central operating shaft, a contact lever on each of said shafts, a handle on the shaft of the front unit, and a coupling on the shaft of an adjoining unit, said coupling engaging the contact lever of the front unit.
12. The combination of a pair of rheostat units, each comprising an operating shaft, said shafts being in alignment with each other, a contact lever on each of said shafts, a handle on the shaft of the front unit, and a coupling on the shaft of the rear unit and embracing the sides of the contact lever of the front unit.
13. The combination of two rheostat units each comprising an operating shaft in line with each other, and adjustable bendable sheet metal means for coupling said shafts.
14. The combination of two rheostat units each comprising an operating shaft in line with each other, and means for coupling said shafts, said means having a bendable metal portion for shifting one shaft angularly with reference to the other.
15. The combination of two rheostat units each comprising an operating shaft in line with each other, and means for coupling said shafts comprising a bendable portion for securing angular adjustment of said shafts.
16. The combination of two rheostat units each comprising an operating shaft in line with each other, an arm on one of said shafts, and a coupling on the other of said shafts having bendable projections embracing said arm.
17. A rheostat unit having a series of fixed contacts, a contact arm adapted to engage said contacts, a shaft for supporting said arm, and flexible means for supporting said shaft.
18. A rheostat unit comprising a plate having fixed contacts thereon, a contact arm, a shaft supporting said arm, and adjustable means for supporting said shaft for aligning said shaft perpendicular to the plane of the face of said fixed contacts.
19. A rheostat unit comprising a supporting plate, fixed contacts thereon, a contact arm, a shaft for said arm, and a bearing of insulating material for said shaft, said plate having a flexible portion for supporting said bearing.
20. A rheostat unit comprising a plate having a series of fixed contacts circularly arranged thereon, a central shaft, a contact arm carried by said shaft, and a bearing for said shaft adjustably mounted with reference to said plate.
21. A rheostat unit comprising a plate, a series of circularly arranged fixed contacts supported thereon, a central shaft passing through said plate, a contact arm on said shaft, said plate having a yieldable portion near said shaft, and a bearing for said shaft mounted on the yieldable portion of said plate.
22. A rheostat comprising a series of fixed contacts, a contact arm, a contact shoe carried by said arm and engaging said fixed contacts, and a spring carried by said arm for forcing said shoe against said contacts, said spring having a spiral coil seated in a recess in said arm and having its two end portions displaced from each other and both end portions engaging said contact shoe.
23. A rheostat comprising a series of fixed contacts, a contact arm, a contact shoe carried by said arm and engaging said fixed contacts, and a spring having two spiral portions located in a recess in said arm and having an end portion extending from each of said spiral portions and having each end portion engaging said contact shoe.
24. A rheostat having a series of fixed contacts and a contact displaced therefrom, a contact arm, a contact shoe carried by said arm, and a spring located in a recess in said arm, said spring having two spiral portions and an end portion extending from

- 6
- each of said spiral portions, one of said end portions engaging the contact shoe over said series of contacts and the other end portion engaging said shoe over said displaced contact.
25. A rheostat having a series of contacts and a contact arm, and a terminal block, said terminal block having a portion positioned in relation to said arm to also serve as a stop therefor.
26. A rheostat having a series of contacts, a contact arm and a single terminal block for the terminals of said rheostat and also having a portion extending in the path of said arm to serve as a stop therefor.
27. A rheostat comprising a plate, a series of contacts thereon, a contact arm for engaging said contacts, a terminal block secured on the back of said plate and having a pathway for lead wires coming through said plate, said plate having an opening opposite said pathway, a cover plate for said opening, and a common means for securing said terminal block and cover plate in position.
28. A rheostat comprising a series of contacts, a contact arm for engaging said contacts, and a terminal block on said rheostat having side extensions for terminal connections and a middle extension in the path of movement of said arm to serve as a stop therefor.
29. A rheostat comprising a series of contacts and a contact arm, a shaft connected with said arm, a stationary element surrounding the front portion of said shaft, a scale plate carried by said element, said scale plate having inwardly extending yieldable projections adapted to seat in undercut recesses in said element for supporting said scale plate, and a pointer carried by said shaft.
30. A rheostat comprising fixed contacts, a contact arm, a shaft for said arm, a scale plate, a handle on the end of said shaft, and a sheet metal pointer having a bent portion extending into a recess in said handle for locking said pointer in position. 45
31. A rheostat comprising fixed contacts, a contact arm, a shaft therefor, a handle on the end of said shaft, said handle having an inner recess, an element passing through said shaft and extending into the recess in said handle for locking said handle to said shaft, a scale plate, and a pointer having an angular portion also extending into said recess of the handle. 50
32. A rheostat having a series of contacts, a contact arm, a shaft therefor, a bearing for said shaft, and a scale plate carried by said bearing, said scale plate and bearing having interlocking projections and recesses, the projections on said scale plate being yieldable and adapted to make a spring engagement in the recesses of said bearing. 55
33. A rheostat having a series of contacts, a contact arm, a shaft therefor, a bearing for said shaft, and a scale plate carried by said bearing, said scale plate having inwardly extending projections and said bearing having cutaway portions corresponding with said projections and also having recesses in which said scale plate projections seat. 60
34. A rheostat comprising a resistance contact plate, a contact arm, a shaft carrying said contact arm, a bearing block for said shaft, said block being supported on said plate and having a recess in one face of said block, and a contact ring seated against said face of said block and having a projecting portion engaging said recess. 70
